Aubrey J. Grindle
By Cheever & Co. Attest.

UNITED STATES PATENT OFFICE.

RALPH H. BOURNE AND AUBREY J. GRINDLE, OF CHICAGO, ILLINOIS, ASSIGNORS TO GRINDLE FUEL EQUIPMENT COMPANY, OF HARVEY, ILLINOIS, A CORPORATION OF ILLINOIS.

DUST COLLECTOR.

Application filed November 22, 1924. Serial No. 751,482.

To all whom it may concern:

Be it known that we, RALPH H. BOURNE and AUBREY J. GRINDLE, citizens of the United States, residing, respectively, at Chicago and Chicago, in the county of Cook and State of Illinois, have invented a certain new and useful Improvement in Dust Collectors, of which the following is a specification.

10 This invention relates to dust collectors conventionally used in and adjacent to factories of various sorts employing machines throwing into the air a large amount of dust and dirt, which would be injurious to the 15 workmen and the general public were the dust and dirt laden air allowed to circulate generally prior to the removal of such dust and dirt from the air. The invention consists in a novel form of mechanism for producing this well known, desired result; which can be very easily and cheaply made; which is satisfactory in use and is not readily liable to get out of order.

More particularly the invention consists 25 in numerous features and details of construction which will be hereafter more fully set forth in the specification and claims.

Referring to the drawings in which like numerals designate the same parts throughout the several views:

30 Figure 1 is a side elevation, largely in section, with certain parts broken away, illustrating this invention in its preferred form.

35 Figure 2 is a sectional plan view on the line 2—2 of Figure 1.

The preferred form of construction of Figure 1 employs an external case 10 in the form of a fulcrum of an upwardly 40 pointed cone, the upper end of which is closed by a generally horizontal cover 12 perforated at its center to interfit with an upwardly extending pipe or passage 14 for the delivery of cleaned air. The lower end 45 of conical case 10 is united through the agency of suitable flanges 16 with a downwardly pointed dust and dirt discharge cone 18 terminating at its bottom in an opening 20 through which, as shown, the dust and dirt may fall in a pile below the device, or to which a conveyer pipe, not entering into this invention and therefore not shown, may be attached for conducting dust and dirt to a distant point.

50

Concentrically mounted with reference to the central axis of case 10 and with reference to each other and located inside said case are two spaced cylinders 22 and 24 both of greater diameter than the discharge pipe 14 heretofore referred to. Interposed between cylinders 22 and 24 is a spiral partition 26 forming in connection with said concentric cylinders 22 and 24 a spiral air passageway leading from an opening 28, near the top of cylinder 24 approximately twice around the cylinder 22 to finally discharge into the interior 30 of case 10—18 at the lower ends of cylinders 22 and 24. The opening 28 is constantly supplied with air under pressure through a suitable pipe 32 passing through the exterior case wall 10, such air under pressure being pumped into the pipe 32 by any suitable means as, for instance, a conventional fan 34 not entering specifically into this invention and therefore not detailed. The pipe 32 is so positioned with reference to opening 28, that laden air delivered by said pipe 32 impinges tangentially on the inside surface of cylinder 24, thus causing said dust laden air to traverse the screw shaped passage defined by spiral partition 26 and in close proximity to the interior surface of said cylinder 24 with the result that the dust and dirt in said air readily finds its way to vertically disposed slotted openings 36 in the surface of cylinder 24. The ready passage of dirt and dust through case openings 36 is assisted by the presence of stamped inwardly pressed guide plates 38 formed at each opening 36 in the wall of cylinder 24. These plates 38 are formed in quite obvious manner in the operation of cutting perforations 36 in the wall of cylinder 24.

In order to assist in forcing the dust laden air to the interior circumference of cylinder 24, the outer surface of cylinder 22 is provided with a multiplicity of vertically disposed wings 40 so placed as to direct air striking them toward the interior circumference of cylinder 24.

In the operation of the mechanism of this invention, dust laden air is continuously delivered by fan 34 through pipe 32 into the spiral passage between cylinders 22 and 24 and along the interior surface of cylinder 24. As the dust laden air passes around the interior of the cylinder, the heavier dirt and

dust particles engage sooner or later one of the guide plates 38 and pass through slotted passages 36 into the space 42 between members 10 and 24. As soon as the dust and dirt reaches this space, it is no longer propelled by air and drops by gravity in the general interior of space 30 of the machine onto the interior surface of cone 18 down which said dust and dirt slides to opening 20. As the air gradually traverses the helical passage between the cylinders 24 and 26, it is in this manner freed of the dust and dirt which it originally carried, with the result that when it reaches the bottom of cylinder 22, it is for practical purposes clean and said cleaned air thereupon turns and passes out through cylinder 22 and pipe 14 to any desired point to which the latter pipe may lead. This latter outward passage of cleaned air may be produced either by initial pressure in pipe 32 or by suction applied by means not entering into the invention and therefore not shown, applied beyond the figure to pipe 14.

In actual practice results not heretofore experienced with commercial dust collectors have been attained by the mechanism of this invention.

Having thus described our invention, what we claim as new and desire to secure by Letters Patent is:

1. In mechanism of the class described, in combination, an outer case, a pair of concentric spaced cylinders inside the outer case connected together by a spiral partition forming a spiral passage extending from top to bottom of said cylinders, there being in the outer of said concentric cylinders a multiplicity of vertically disposed elongated perforations opening into said spiral passage, means introducing dust laden air from outside the device to the upper end of said spiral passage in a direction tangential to the inner surface of the larger of said two concentric cylinders, means conducting cleaned air from the bottom of said spiral passage out of the top of the machine and means conducting dirt from the bottom of machine.

2. In mechanism of the class described, in combination, an outer case of upwardly tapered conical form, a pair of concentric spaced cylinders inside the outer case connected together by a spiral partition forming a spiral passage extending from top to bottom of said cylinders, there being in the outer of said concentric cylinders a multiplicity of vertically disposed elongated perforations opening into said spiral passage, means introducing dust laden air from outside the device to the upper end of said spiral passage in a direction tangential to the inner surface of the larger of said two concentric cylinders, means conducting cleaned air from the bottom of said spiral passage out of the top of the machine and means conducting dirt from the bottom of machine.

3. In mechanism of the class described, in combination, an outer case, a pair of concentric spaced cylinders inside the outer case connected together by a spiral partition forming a spiral passage extending from top to bottom of said cylinders, there being in the outer of said concentric cylinders a multiplicity of vertically disposed elongated perforations opening into said spiral passage, a guide plate 38 at each such perforation so positioned as to intercept dirt passing circumferentially of the outer of the two concentric cylinders and guide it outward into the space immediately adjacent to the outer case, means introducing dust laden air from outside the device to the upper end of said spiral passage in a direction tangential to the inner surface of the larger of said two concentric cylinders, means conducting cleaned air from the bottom of said spiral passage out of the top of the machine and means conducting dirt from the bottom of machine.

4. In mechanism of the class described, in combination, an outer case of upwardly tapered conical form, a pair of concentric spaced cylinders inside the outer case connected together by a spiral partition forming a spiral passage extending from top to bottom of said cylinders, there being in the outer of said concentric cylinders a multiplicity of vertically disposed elongated perforations opening into said spiral passage, a guide plate 38 at each such perforation so positioned as to intercept dirt passing circumferentially of the outer of the two concentric cylinders and guide it outward into the space immediately adjacent to the outer case, means introducing dust laden air from outside the device to the upper end of said spiral passage in a direction tangential to the inner surface of the larger of said two concentric cylinders, means conducting cleaned air from the bottom of said spiral passage out of the top of the machine and means conducting dirt from the bottom of machine.

5. In mechanism of the class described, in combination, an outer case, a pair of concentric spaced cylinders inside the outer case connected together by a spiral partition forming a spiral passage extending from top to bottom of said cylinders, there being in the outer of said concentric cylinders a multiplicity of vertically disposed elongated perforations opening into said spiral passage, means introducing dust laden air from outside the device to the upper end of said spiral passage in a direction tangential to the inner surface of the larger of said two concentric cylinders, means conducting cleaned air from the bottom of said spiral passage out of the top of the machine, means conducting dirt from the bottom of the machine, and wings 40 on the outer circumfer-

ence of the inner of the concentric cylinders for the purposes set forth.

6. In mechanism of the class described, in combination, an outer case of upwardly 5 tapered conical form, a pair of concentric spaced cylinders inside the outer case connected together by a spiral partition forming a spiral passage extending from top to bottom of said cylinders, there being in the 10 outer of said concentric cylinders a multiplicity of vertically disposed elongated perforations opening into said spiral passage, means introducing dust laden air from outside the device to the upper end of said 15 spiral passage in a direction tangential to the inner surface of the larger of said two concentric cylinders, means conducting cleaned air from the bottom of said spiral passage out of the top of the machine, means 20 conducting dirt from the bottom of machine, and wings 40 on the outer circumference of the inner of the concentric cylinders for the purposes set forth.
7. In mechanism of the class described, 25 in combination, an outer case, a pair of concentric spaced cylinders inside the outer case connected together by a spiral partition forming a spiral passage extending from top to bottom of said cylinders, there being 30 in the outer of said concentric cylinders a multiplicity of vertically disposed elongated perforations opening into said spiral passage, a guide plate 38 at each such perforation so positioned as to intercept dirt passing 35 circumferentially of the outer of the two concentric cylinders and guide it outward into the space immediately adjacent to the outer case, means introducing dust laden air from outside the device to the upper end of said spiral passage in a direction tangential to the inner surface of the larger of said two concentric cylinders, means conducting cleaned air from the bottom of said spiral 40 passage out of the top of the machine, means 45 conducting dirt from the bottom of machine, and wings 40 on the outer circumference of the inner of the concentric cylinders for the purposes set forth.

said spiral passage in a direction tangential 40 to the inner surface of the larger of said two concentric cylinders, means conducting cleaned air from the bottom of said spiral passage out of the top of the machine, means 45 conducting dirt from the bottom of the machine, and wings 40 on the outer circumference of the inner of the concentric cylinders for the purposes set forth.

8. In mechanism of the class described, in combination, an outer case of upwardly 50 tapered conical form, a pair of concentric spaced cylinders inside the outer case connected together by a spiral partition forming a spiral passage extending from top to bottom of said cylinders, there being in the 55 outer of said concentric cylinders a multiplicity of vertically disposed elongated perforations opening into said spiral passage, a guide plate 38 at each such perforation so positioned as to intercept dirt passing 60 circumferentially of the outer of the two concentric cylinders and guide it outward into the space immediately adjacent to the outer case, means introducing dust laden air from outside the device to the upper end of said 65 spiral passage in a direction tangential to the inner surface of the larger of said two concentric cylinders, means conducting cleaned air from the bottom of said spiral 70 passage out of the top of the machine, means 75 conducting dirt from the bottom of machine, and wings 40 on the outer circumference of the inner of the concentric cylinders for the purposes set forth.

In witness whereof, we have hereunto 75 subscribed our names.

RALPH H. BOURNE.
AUBREY J. GRINDLE.
